FRAME FOR BUILDING OPENINGS
 Sven Eric Persson, 1676 Commerce Drive, Stow, Ohio
 Filed Jan. 4, 1963, Ser. No. 249,477
 4 Claims. (Cl. 189—75)

The present invention relates to metal frames for windows, doors and other openings in buildings and more particularly is directed to such frames constructed of extruded or formed metal sections connected together with insulation therebetween.

Heretofore the metal framing used in building construction in which closure members such as doors or sashes are mounted has not provided adequate insulation between the outer frame portion and the inner frame portion or between the frame portions and sash or door portion. In some building constructions only a one piece or unitary frame member is used while in other building constructions when an outer and inner frame portion were used, no rigid connection therebetween with insulation interposed thereat was provided.

An object of the present invention is therefore to provide metal frames formed of rigidly connected outer and inner frame portions with interposed insulation for use in construction purposes in which doors or sashes are to be mounted.

Another object of the present invention is to provide rigidly connected outer and inner frame portions with insulation at the point of connection therebetween as well as between the frame portions and the sash or door member.

A further object of the present invention is to provide metal frames composed of inner and outer portions wherein in one of the frame portions has a U-shaped groove forming portion into which a flange of the other frame portion is inserted with insulation therebetween, and the U-shaped portion is compressed to grip the straight portion and the interposed insulation to provide an effective insulated rigid connection between the frame portions.

A still further object of the present invention is to provide a rigid insulated connection between portions of a frame member wherein ribs are provided on cooperating flange and groove members.

An additional object of the present invention is to provide a novel mounting of a frame of a window or door to the wall of a building.

Further objects of the invention will become apparent when considering the following description taken in conjunction with the drawings in which:

FIGURE 1 is a perspective view showing a window and sash mounted in a frame disposed in a building; and

FIG. 2 is a section taken along the lines II—II of FIG. 1.

In FIG. 1 there is shown a window structure 1 including a frame 2 and a sash 3 carrying the window pane 4 mounted in an opening 5' of wall 5. If desired, the sash 3 can be made of an inner portion 3a and an outer portion 3b each provided with a window pane 4 as shown in FIG. 2 and in prior U.S. Patents Nos. 2,694,841; 2,838,109; 2,845,116 and 2,975,492. As can be seen the window panes 4 are mounted in sash portions 3a and 3b by means of gaskets or sealing strips 7. The frame 2 consists of an inner frame portion 8 and an outer frame portion 9. The frame portions 8 and 9 are generally made from metal and preferably from extruded or formed metal such as aluminum or steel or an alloy thereof. Inner frame portion 8 comprises a U-shaped channel portion 11, a U-shaped portion 12 and a straight flange-like portion 13.

The U-shaped channel portion 11 has depressions 14 into which legs 15 of an anchor 16 fit. The anchor 16

has another leg 17 bolted into the interior section 18 of wall 5 by means of anchor bolt 19. There are a number of anchors 16 spaced around the opening in interior wall 18 in order to effectively anchor the inner frame portion 8 therein.

The U-shaped portion 12 has a leg 12' which abuts against the covering material over the interior wall 18 such as plaster, dry wall etc., while leg 12'' serves as an abutment against which anchor 16 abuts for lending strength and rigidity thereto. Leg 12'' is also a common leg between U-shaped portion 12 and U-shaped channel portion 11.

Straight flange portion 13 extends from U-shaped channel portion 11 at substantially right angles to leg 11' thereof. Teeth or ribs 13' and 13'' project from both sides of straight flange portion 13 and are spaced from each other.

Outer frame portion 9 has a substantially U-shaped locking portion 20 of which the flange-like legs 20' and 20'' have inwardly directed ribs or teeth 21 spaced from each other. The ribs or teeth 21 are intermediately spaced with respect to the ribs or teeth 13' of straight flange portion 13 of the inner frame portion 8.

The flange-like leg 20'' of U-shaped locking portion 20 is normally disposed as shown in broken lines before outer frame portion 9 is rigidly connected to inner frame portion 8. A U-shaped piece of insulation 22 is placed around flange portion 13, then the U-shaped locking portion 20 with the flange-like leg 20'' in its normal position is moved to embrace insulation 22 and flange portion 13, and thereafter the U-shaped locking portion 20 is clamped onto insulation 22 and straight flange portion 13 with the ribs 13', 13'' and 21 intermeshing so that a rigid connection is effected between inner and outer frame portions without the use of screws, rivets or such similar devices. The connection between the two frame portions is so rigid that extremely large forces are necessary to separate the two portions once they are interconnected.

At the inner edge of leg 20', there is integral therewith a section 23 having a groove 24 therein. Groove 24 has a gasket or sealing strip 25 disposed therein.

Outer frame portion 9 has a flange-like leg 26 which extends toward the exterior section 27 of wall 5 and caulking compound is disposed therebetween at 28 to form a tight seal.

On the other side of web 10 of channel member 11 of inner frame portion 8 there are spaced abutments 29. A stop member 30 of U-shaped or channel cross section has flanges 31 and 32 which engage against abutments 29. Channel member 30 is held in place against web 10 of channel portion 11 by means of bolts, screws or some similar retaining means (not shown), or by a fish-hook like self-locking device against abutments 29.

Flange 32 has grooves 33 therein which receive the edges of a sealing strip or gasket member 34. As can be seen, sealing strip 25 abuts against sealing strip 34, and section 23 has a wider flange-like leg 35 abutting against sealing member 34.

Inner portion 3a of sash 3 has a straight flange 36 on the outer periphery thereof serving as means to engage and cooperate with stop member 30 of the frame. Ribs 37 are disposed on each side of straight flange 36 and are provided with teeth-like projections 38. A sealing strip 39 having a U-shaped cross section embraces flange 36 and has its free edges positioned between flange 36 and members 37 with the projections 38 of the members 37 engaging and gripping and securely clamping sealing strip 39.

Sealing strip 39 abuts against sealing strip 34, and against a projecting flange 30' of stop member 30.

The material forming the insulation or thermal-break

between the inner and outer frame portions 8 and 9 is a material with a low conductance such as vinyl, neoprene, rubber, Hypalon or other plastic and synthetic materials.

The sealing strips or gaskets are formed of a flexible material such as soft vinyl, neoprene, rubber, or sponge material such as sponge neoprene.

As can be discerned, the present invention comprises a rigid, strong and insulated connection between frame portions of a frame member in which a door or sash is to be mounted, effective insulation between the frame member and the sash or door member and a mounting of the frame member to the wall of a building.

Having described my invention, I claim:

1. A frame member for an opening in a wall of a building, comprising an inner frame portion and an outer frame portion, cooperating connecting means on each portion for providing a rigid and strong interconnection between said portions, said connecting means comprising a flange on one frame portion, a channel member on the other frame portion, said flange extending into said channel member, heat-insulating material between said flange and said channel member, a sealing member carried by said channel member, a sealing strip carried by said one frame portion, said sealing member and said sealing strip both being of readily deformable material and being pressed against each other in abutting and sealing relationship, a closure member mounted in said frame member, a peripheral flange on said closure member, a sealing member embracing said peripheral flange, said embracing sealing member being of readily deformable material and being pressed against said sealing strip in sealing relationship when the closure member is in closed position, said channel member having a pair of spaced legs between which said flange is disposed, one of said legs being on the same side of said flange as said closure member, said one leg having an outwardly directed extension, the outer edge of said extension having a flange directed away from the closure member and which defines with the bottom of said channel a groove opening away from the closure member, thereby to provide a forward

finished edge of substantial depth and width for said outer frame portion.

2. A frame member for an opening in a wall of a building comprising a forward frame portion and a rear frame portion, a flange on one of said frame portions, a channel member on the other of said frame portions, said flange extending into said channel member, a readily deformable sealing strip carried by said one frame portion, a groove in said other frame portion confronting said sealing strip, and readily deformable heat-insulating material disposed in said channel on both sides of said flange and in said groove and pressed into resilient contact with said sealing strip, said heat-insulating material comprising an integral piece of material extending about said flange and into said groove.

3. A frame member as claimed in claim 2, said heat-insulating material disposed in said groove having a portion that emerges from said groove and that is folded back on itself, said emerging portion being in contact with said sealing strip.

4. A frame member as claimed in claim 2, and a closure member mounted in said frame member, a peripheral flange on said closure member, and a sealing member embracing said peripheral flange, said embracing sealing member being of readily deformable material and being pressed against said sealing strip in sealing relationship when the closure member is in closed position.
